UNITED STATES PATENT OFFICE

ELMER E. HICKEN, OF COLLINGSWOOD, NEW JERSEY

LOCOMOTIVE TENDER

Application filed January 12, 1929. Serial No. 332,212.

One object of my invention is to construct the tender of a locomotive in which stoking mechanism is used, so that the stoker-engine can be mounted on the tender.

5 A further object of the invention is to so construct the forward end of the tender that the stoker engine can be located between the side of the tender and the stoking mechanism.

The invention can be applied either to a 10 tender having a rectangular water section or to a tender having a cylindrical water section.

In the accompanying drawings:

Fig. 1 is a side view of the front portion of 15 a locomotive tender illustrating my invention;

Fig. 2 is a sectional plan view on the line 2—2, Fig. 1;

Fig. 3 is a transverse sectional view on the 20 line 3—3, Fig. 2;

Fig. 4 is a sectional view on the line 4—4, Fig. 2;

Fig. 5 is a side view of a tender having a 25 cylindrical tank and illustrating my invention;

Fig. 6 is an end view of the tender shown in Fig. 5;

Fig. 7 is an enlarged sectional view on the 30 line 7—7, Fig. 5, illustrating the engine supporting brackets; and

Fig. 8 is a sectional view on the line 8—8, Fig. 5, drawn to an enlarged scale.

Referring to the drawings, 1 is the base frame of the tender, made in the present instance in a single casting and having a longitudinal hollow beam 2 with integral bumpers 3 at each end, and projecting from the beam are arms 4. Between the arms are webs 5 which form the main floor of the fuel section 40 and a part of the floor of the water section.

At the forward end of the base frame the webs are extended as at 5^a to form floors which extend to the side walls of the tender body. In these floors are openings 7—7^a, but 45 these openings may be closed by plates if desired, or the floors may be solid.

The side walls 8 of the tender, in the present instance, extend to the points *x*, Fig. 2, and are turned under as at 8^a to form a part of 50 the bottom of the water section A of the

tender, being secured to the webs of the base, as illustrated in Fig. 4.

The end plates 9 at the forward end of the tender are secured to flanges 10 projecting upwardly at the ends from the base and these 55 flanges are curved as at 10^a, the plates being bent to conform to this curve.

The plates 9 at the sides are turned under the extensions 5^a of the bottom of the tender as clearly shown in Figs. 1, 2 and 3, and lap over the forward ends of the side plates 8. This construction, however, may be modified without departing from the essential features 60 of the invention.

Partition plates 11 are cast integral with 65 the base and are flanged at their upper edges as at 12, and mounted on the flanged portions of the plates is the floor plate 13, which has the usual slot 14 therein covered by adjustable or removable gate plates. These partition 70 plates extend transversely at the rear of the fuel chamber as at 11^a, Figs. 1 and 2.

Located at the front end of the tender and at one side thereof is a compartment 15, separated from the water section of the tender 75 by a vertical plate 16. This plate is flanged in the present instance and is firmly secured to the partition plates 11 and the side walls of the tender.

Projecting from the frame 1 are supports 80 17. Mounted on these supports is a stoker engine *a* of any suitable type. The supports may be formed as projections from the floor 5^a, as illustrated in Figs. 1 and 3, or they may be in the form of brackets as at 17^a, in Figs. 85 5, 6 and 7. The type of support will vary somewhat in the particular type of base frame used and the particular type of engine. The engine may be located on either side of the tender, depending upon the type of stoker. 90

The compartment 15 is preferably closed at the side facing the stoker by a plate 18, which may be detachably secured in position, and at the top of the compartment a horizontal plate 19, having upturned flanges in the present instance, may form the ceiling of this compartment 15. Above the plate 19 is a compartment 20 which may be used as a receptacle for tools, etc., and this compartment is 95 closed by a roof plate 21, flanged at the edges 100

and secured to an extension 18^a of the plate 18. Doors 22 may be provided for the compartment 20 and doors 23 may be provided for the compartment 15, and, if desired, there 5 may be an opening at the side of the compartment enclosed by a suitable cover plate 24, Fig. 5.

On the opposite side of the tender are storage compartments 26 and 27, which may be 10 provided with doors of any suitable type.

The water section of the tender illustrated in Figs. 1, 2 and 3 is rectangular in cross-section, but in Figs. 5, 6 and 7 my invention is applied to a tender in which the water section

15 A is semi-cylindrical in cross-section, the side walls 8^b being curved and downwardly flanged as at 8^c to fit against out-turned flanges 5^b of the webs 5, forming a part of the base structure, the two flanges being 20 secured together preferably by outside rivets as shown in Fig. 8.

The roof plate 28 is preferably flat as shown in Fig. 6 and has up-turned flanges 29 which are secured to upwardly projecting 25 flanges 30 at the upper edge of the curved side plates 8^b.

The fuel section B' is formed in the ordinary manner and is provided in the present instance with guides for a stoker which is 30 driven by the engine located in the space 15^a at one side of the stoker compartment.

I claim:—

1. The combination in a locomotive tender, having a base; a body portion; and partition 35 plates separating the fuel section of the tender from the water section thereof, the fuel section being designed to receive stoker mechanism, the forward end of the tender having a compartment at one side of the fuel section for the engine of the stoker mechanism.

2. The combination in a locomotive tender, of a base frame made in a single casting and having at its forward end integral supports 45 for a stoker engine, said supports being located at one side of the stoker chamber.

3. The combination in a locomotive tender, of a base frame made as an integral casting, having upright partition plates separating 50 the fuel section from the water section, said plates terminating short of the forward end of the tender, forming a space for a stoker engine; and stoker engine supports on the base projecting into this space.

55 4. The combination in a locomotive tender, of a base frame made in a single casting, having a longitudinal beam with bumpers at each end and transverse arms projecting from the beam; side plates secured to the 60 base frame; vertical partition plates separating the stoker compartment of the fuel section from the water section of the tender, the plate on one side terminating short of the forward end of the tender and forming 65 a space for the stoker engine; stoker engine

supports projecting into this space; an enclosure for said engine; and a receptacle above the space occupied by the engine.

5. The combination in a locomotive tender, of a base made in a single casting having a longitudinal beam; bumpers at each end of the beam; transverse arms projecting from the beam between the bumpers, said base having downwardly turned flanges; curved side plates having downwardly turned flanges at their lower edges secured to the flanges of the base; a roof plate having up-turned flanges to which the upper edges of the side plates are secured, the forward end of the tender being rectangular in cross-section and having a space at the centre for stoker mechanism; a compartment at one side beyond the water section of the tender for a stoker engine; and supports made integral with the base frame on which the stoker engine is mounted.

DISCLAIMER

1,733,016.—*Elmer E. Hicken*, Collingswood, N. J. LOCOMOTIVE TENDER. Patent dated October 22, 1929. Disclaimer filed May 13, 1931, by the patentee.

Hereby enters this disclaimer of that particular part of the claim in said specification which constitutes claim 1 thereof and which is in the following words; to wit:

“The combination in a locomotive tender, having a base; a body portion; and partition plates separating the fuel section of the tender from the water section thereof, the fuel section being designed to receive stoker mechanism, the forward end of the tender having a compartment at one side of the fuel section for the engine of the stoker mechanism.”
